UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

ELASTIC-FLUID TURBINE.

No. 924,898.

Specification of Letters Patent.

Patented June 15, 1909.

Application filed February 24, 1909. Serial No. 479,697.

To all whom it may concern:

Be it known that I, WILLIAM L. R. EMMET, a citizen of the United States, residing at Schenectady, county of Schenectady, State of New York, have invented certain new and useful Improvements in Elastic-Fluid Turbines, of which the following is a specification.

This invention relates to elastic fluid turbines wherein the moving buckets are carried by a drum and the stationary or intermediate buckets by the casing.

The object of my invention is to provide an effective means for dividing such a turbine into stages without the use of diaphragms, and one which is capable of operating with a small clearance between it and the drum.

For a consideration of what I believe to be novel in my invention, attention is directed to the accompanying description and claims appended thereto.

In the accompanying drawing which is illustrative of one of the embodiments of my invention, Figure 1 is a partial axial section of a turbine; Fig. 2 is a detail view of a portion of one of the nozzles; and Fig. 3 is an enlarged view of the means employed to reduce leakage.

1 indicates the annular stationary casing of a turbine having an internal shoulder 2 that receives and supports the diaphragm 3. This casing is split axially as usual to enable the parts to be assembled. In the shoulder is a port 4 delivering steam to the nozzle 5 supported thereby. This nozzle comprises a plurality of closely associated sections and may be expanding or non-expanding in character. The intermediate buckets 6 may be supported in any suitable manner. I have shown each two rows mounted in segmental rings 7 that are let into grooves in the casing. The moving or wheel buckets 8 are mounted on the drum 9 and are secured as are the stationary buckets by means of channel bars 10 that are let into the drum on one hand and into the rings 7 on the other. Both rotary and stationary buckets are provided with covers to confine the steam to its proper path and to reduce leakage.

50 In order to divide the turbine into stages nozzles 11 are provided whose cross-sectional areas increase by stages as the volume of steam to be handled increases. These nozzles comprise an outer ring 12 and an inner

ring 13. Both of these rings are split axially into segments, as many as desired, to enable the turbine to be assembled, and also to permit each of the segments to expand and contract independently of the other or others. The sheet metal nozzle partitions 14 may be secured in place in any suitable way, for example by casting them into both rings. The nozzle 4, the stage nozzles 11 and the stationary and moving buckets or vanes 6 and 8 co-operate to form the working passage of the turbine or that through which the steam flows as it performs useful work, *i. e.*, driving the rotor.

In turbines of the character described there is a difference in pressure more or less great between opposite sides of the nozzle, which difference causes steam to flow through the clearance between the bore of said nozzle and the peripheral surface of the drum. If the parts are of large diameter the steam thus lost through the clearances may be a very considerable item, and seriously affect the economy of operation. Another factor to be taken into consideration is the unequal distortion of the stationary and rotary parts due to temperature changes brought about by changes in pressure occasioned by load variations. Also that under certain conditions the peripheral surface of the drum may be caused to rotate slightly out of the path of a true circle due to springing or whipping of the shaft or other cause. It is also to be borne in mind that the moving buckets are traveling past the nozzle and stationary buckets at a high rate of speed, varying from about 225 feet per second in marine turbines to about 425 feet per second in land turbines.

The troubles incident to distortion and whipping can be largely or entirely obviated by making the clearances large, in which case there is an abnormal leakage of steam accompanied by a reduction in economy. On the other hand, the leakage losses can be greatly reduced by making small clearances, but here is encountered the difficulty of insuring free operation of the parts without contact when distortion, or springing or whipping of the shaft takes place. The problem thus presented is to provide a means which will have all of the advantages of the arrangements above specified with none of their disadvantages. To meet these exacting requirements, the ring 13 is made in

a special way. In reality it comprises two concentric rings an inner and an outer united at one side only and separated at other points by a space. In its bore are or may be 5 teeth or projections 15 integral or otherwise, each of which presents a relatively narrow surface to the drum. The end surfaces of the teeth are separated from the drum by a relatively small clearance to reduce leakage. 10 This arrangement of alternate teeth and 15 grooves further acts to retard leakage. A simple and satisfactory way to make these teeth is to cut a screw-thread of coarse pitch in the ring and to plug up the end of the groove between threads on the low pressure 20 side, or parallel grooves may be cut in the ring. The metal directly back of these projections is cut away as at 16, and the cross-section of the metal at some point such as 25 17 is somewhat reduced, or at least is not greatly increased, so that the portion 18 directly carrying the teeth or projections can yield outwardly of the drum 9 by undue distortion, 30 springing or whipping of the shaft moves out 35 of its true path and rubs thereon. The cross-section of the inner ring 13 is substantially U-shaped with the legs of the U extending parallel to the drum, one leg forming a support for the nozzle partitions while the other 40 leg is free to move under the conditions specified. The movements referred to herein measured in fractions of an inch would be 45 very small indeed yet nevertheless they are of the utmost importance, and provision must be made to compensate therefor if the best results are to be obtained.

Another important feature to be noted is 50 that the metal at 19 which is in direct line with the solid part of the ring is cut back or 55 away from the drum so that it can never be engaged thereby no matter how great the distortions of the drum, casing or parts carried by one or all of said turbine members may be. In many cases it is also desirable 60 to cut away that portion of the drum directly in line with the solid part of the ring 13, as shown, and for the same purpose. Owing to the fact that the points or ends of the teeth on the ring are relatively thin and easily 65 heated, they will in case of accidental rubbing wear away much faster than the drum, and without special injury to the latter. It is to be noted that the annular slot 16 in the ring is somewhat longer axially than is the 70 space occupied by the teeth or projections. This is done so that the part 18 can expand and increase its diameter when heated, and contract and decrease its diameter in cooling without being impeded in said actions. The 75 arrangement also prevents serious injury when for any reason the drum strikes the teeth or projections at some portion of their circumference and moves the part 18 bodily at the point of contact.

80 When the turbine is operating there will be

a thin annular film of steam leaking axially through the clearance space between the teeth and the adjacent finished surface of the drum because it is impossible to cut off all leakage where the parts must be held out of 85 mechanical contact. By means of the arrangement shown I can, however, reduce this to a minimum by reducing the clearance to a much smaller amount than would be practicable or safe if the inner nozzle rings 13 90 were made solid. In addition to the small clearance between surfaces acting to reduce leakage, the grooves between the teeth also perform the same office. The flow of steam is axially and in an annular and very thin 95 film and in passing the mouths of the grooves little whirls or eddies are created in said film which act to materially choke back or retard its flow.

As an additional means to reduce leakage 100 buckets may increase in height by successive steps instead of gradually. With this arrangement the steam tends to pass over the clearances instead of out of them.

By reason of my improved construction I 105 am able to dispense with diaphragms in certain portions of the turbine, usually the low pressure end, which commonly extends from the casing to a point near the shaft. This results in mechanical simplification in many 110 cases, reduces the total length of the machine, and reduces the weight of the parts.

If the inner ring 13 was made solid and rubbing took place between the wall of its bore and the drum, the heat generated at the 115 contacting surfaces would cause the ring to expand and since it is confined by the turbine casing this heating would cause the wall of its bore to move toward the drum. Abnormal heating of the drum would cause it to 120 enlarge and hence the effects of the heating would be accumulative and would continue until the metal of the ring or drum or both commenced to flow. This action would continue until the contacting surfaces were actually separated by the melting or flowing of the contacting surfaces. By making the inner ring 13 in segments and with the capacity to expand outwardly I avoid the very 125 great objections noted above and at the same time keep the leakage down to a low value. In some cases I may omit the teeth 15 and make the bore of the ring portion 18 smooth but it is better to use the teeth because they are effective in reducing leakage.

I may use my invention on some or all of the rows of intermediate buckets. I may also use my invention to a greater or less advantage on reaction turbines where the losses due to leakage are material ones.

In accordance with the provisions of the patent statutes, I have described the principle of operation of my invention, together with the apparatus which I now consider to represent the best embodiment thereof; but

I desire to have it understood that the apparatus shown is only illustrative, and that the invention can be carried out by other means.

What I claim as new and desire to secure by Letters Patent of the United States, is,—

- 5 1. In a turbine, the combination of a casing, a rotor, buckets carried by the casing and also by the rotor, and means for dividing the casing into stage compartments, which is provided with a leakage reducing means comprising a segmental ring the wall of whose bore is located in close proximity to a surface on the rotor and which is free to expand outwardly under temperature changes.
- 10 2. In a turbine, the combination of a casing, a rotor, buckets carried by the casing and also by the rotor, and a means for dividing the casing into stage compartments which includes a leakage reducing means comprising a segmental ring that is composed of two principal portions, one of which is relatively fixed in position while the other is supported at one side only and is free to expand outwardly when heated.
- 15 3. In a turbine, the combination of a casing, a drum located therein, rows of buckets mounted on the drum for driving it, fluid directing means arranged in rows and carried by the casing and located between the rows of wheel buckets, and a means for uniting the ends of certain of the fluid directing means and reducing leakage comprising a ring the surface of whose bore co-operates with a relatively movable part of the turbine, the said ring being separated from its support for a portion of its axial length by a space to permit of the ring expanding outwardly.
- 20 4. In a turbine, the combination of a casing, a drum located therein, rows of buckets mounted on the drum for driving it, stationary buckets carried by the casing and arranged in rows between the wheel buckets, and a nozzle for dividing the casing into stages and discharging motive fluid against the buckets on the drum, the said nozzle being annular and provided with a ring which surrounds the drum is provided with leakage reducing means in its bore and is cut

away directly in the back of said means to 50 permit of distortion.

5. In a turbine, the combination of a casing, a rotor located therein, rows of buckets mounted on the rotor for driving it, fluid directing devices carried by the casing, a structure carried by said devices for reducing leakage and comprising a ring attached to said devices and a second ring supported by the first at one side only and separated at other points to permit of independent expansion and contraction, and means on the second ring that co-operate with the rotor to reduce leakage.

6. In a turbine, the combination of a casing, a rotor located therein, rows of buckets 65 mounted on the rotor for driving it, devices carried by the casing for directing fluid against the buckets, the said buckets and devices co-operating to form the working passage, and a means for reducing the effects 70 of unequal distortion and leakage in the working passage of the turbine comprising concentric rings united at one side only and separated by a space at other points, one of said rings being supported by one of the 75 main elements of the turbine while the other ring is free to expand and contract.

7. In a turbine, the combination of stationary and rotary parts, a means dividing the turbine into stage compartments and 80 preserving a difference of pressure therein, and a leakage reducing device comprising a segmental ring that is supported at one end only and is free to expand outwardly under an increase in temperature.

8. As an article of manufacture, a nozzle structure comprising outer and inner rings, the inner ring being substantially U shaped in cross-section with the legs of the U extending axially, and partitions for directing the 90 fluid which connect the outer and inner rings.

In witness whereof, I have hereunto set my hand this 23rd day of February, 1909.

WILLIAM L. R. EMMET.
